Robert H. Lawson, Laconia, N. H., assignor to Scott & Williams, Incorporated, Laconia, N. H., a corporation of Massachusetts

Application November 1, 1954, Serial No. 465,883

12 Claims. (Cl. 66—13)

This invention relates to a knitting method and machine and has particular reference to the formation of rib tops or other ribbed bands on half hose or other circular machines having cylinder and dial needles.

The patent to R. W. Scott No. 1,641,101, dated August 30, 1927, describes in detail mechanism and procedure involved, starting on bare needles, in the formation of rib tops of half hose and the transfer of loops from dial needles to cylinder needles which were inactive during the formation of the rib top.

The rib top so formed heretofore had relatively unsatisfactory appearance and characteristics, and improved method and mechanism for the formation of rib tops have been devised and form the subject matter of my application, Serial No. 263,377, filed December 26, 1951, now Patent No. 2,719,415.

The present invention relates to the securing of proper sinker operation in the formation of rib tops or ribbed bands and applies to the formation of rib fabric in accordance with both said Scott patent and the improved procedure of my application. For clarity of description and also because it is particularly applicable to the improved method and machine of said application, the invention will be described specifically as applied to the method and machine of my prior application.

As described in said Scott patent, during the formation of the welt preceding the formation of a rib top, the sinkers had imparted to them the normal movements for the formation of plain fabric. At the beginning of rib knitting, the welt had to be forced inwardly by abnormal movements of sawtooth sinkers and for this purpose the sawtooth sinkers were drawn outwardly to an abnormal extent so that when moved inwardly by the rib knock-over cam they would engage and impart considerable movement to the welt to provide the necessary tensioning for the formation of the initial rib stitches. The abnormal outward movement was imparted prior to the drawing of stitches and the subsequent inward movement of the sinkers occurred directly following the drawing of the loops. The continued proper formation of rib stitches required continued action of the sinkers through abnormal ranges of movement and, consequently, the sinker controlling operations just described were continued throughout the formation of a rib top. In my application referred to above, these same sinker movements of the Scott patent were involved to control the proper formation of rib fabric.

It has been found, however, that in taking a new hold on the rib stitches near where they are being formed, the sinkers would sometimes disturb them to such an extent that tucks and/or irregularities resulted.

It is the general object of the present invention to provide a modification of the sinker operations to avoid the troubles just mentioned. Abnormally great sinker movements are required to impart tension to the rib fabric as it is being formed, but in accordance with the present invention, these abnormally large movements of the sinkers are caused to take place remote from the point of

2

stitch formation, and in fact may be less than has been usual. In accordance with the present invention, therefore, the cam which formerly effected the abnormal withdrawal during the transition from welt to rib knitting is located where it merely serves to prevent the sinkers from moving too far inwardly to prevent the welt from passing freely between the sawteeth of the sinkers and the dial fins. After the stitch formation is entirely completed, the sinkers are withdrawn by an additional cam and they are then free to move inwardly under the action of their spring band to effect proper take-up and tensioning of the rib fabric without, however, releasing their tension and then abruptly exercising force on the fabric during the formation of a stitch such as might lead to tucking or irregularities.

The foregoing general object of the invention and other more detailed objects particularly relating to features of construction and operation will become apparent from the following description read in conjunction with the accompanying drawings, in which:

Figure 1 is an inside development of the cams for acting upon the butts of cylinder needles in a machine of the type described in said Scott patent;

Figure 2 is a horizontal section showing, in particular, cams for acting upon the hook and point members constituting two-part dial needles;

Figure 3 is a development looking inwardly at the cylinder and dial needles and associated elements, the sinkers associated with the cylinder needles being shown in section;

Figure 4 is a plan view showing, in particular, various sinker-controlling cams and the operating devices therefor; and

Figures 5 to 10, inclusive, are enlarged axial sections showing the relationships of the cylinder and dial needles and sinkers during rib knitting, the various sections being taken on the axial planes indicated at 5, 6, 7, 8, 9 and 10 in Figures 1, 2, 3 and 4.

The half hose machine which is illustrated is essentially as described in said Scott patent, modified in accordance with said Lawson application, and, accordingly, there are illustrated only those changes and parts which are particularly concerned with the attainment of the objects of the present invention. As will more fully appear hereafter, transfer operations are carried out precisely as described in said Scott patent and, hence, have not been illustrated.

The half hose machine comprises the slotted needle cylinder 2 in which are mounted latch needles which are designated 4' and 4'', there being designated by 4' those alternate needles which are active during rib knitting while there are designated at 4'' the intermediate needles which are inactive during rib knitting. As is usual, these needles are provided with butts arranged to be acted upon by suitable cams, there being made provision for differentiating the needles of the groups 4' and 4'' by means of jacks which are not illustrated; the arrangement being as in said Scott patent.

When making 1 x 1 rib, two types of sinkers are provided in alternation about the needle cylinder between the needles thereof. Sinkers indicated at 6 are provided with sawteeth 8 and usual nibs 10 and are located to the left of, or behind, from the standpoint of direction of cylinder rotation each of the active needles 4', as illustrated particularly in Figure 3. The intermediate sinkers 12 are without the sawteeth 8 and are provided at the rear of the inactive needles 4''. These sinkers of both sets are mounted in conventional fashion and have conventional waves imparted thereto, as described in said Scott patent, by cams acting upon their butts. The sinkers are urged inwardly by the conventional spring band. If other types of ribs, such as 2 x 1 or 3 x 1 are

desired, certain of the sawtooth sinkers 6 may be replaced by plain sinkers 12.

The usual slotted dial is provided at 14 and has fins 15 provided on its underside for cooperation with the sawtooth sinkers to assist in the drawing of the fabric inwardly from the cylinder needles. These fins 15 differ from those described in said Scott patent and my application by reason of the provision of inwardly directed abrupt shoulders 17 which, as will appear hereafter, cooperate in engaging the rib stitches to effect proper take-up action.

The dial is automatically vertically movable as described in the Scott patent. It is raised in the formation of the welt to provide room for the formation of the welt fabric and is then lowered with respect to the cylinder for knitting of the rib. It is then again raised after transfer.

Within radial slots in the dial 14 there are mounted for relative sliding movements the hook members 16 and the cast-off or point members 20 constituting the dial needles. The hook members 16 are provided with the usual hooks 18 while the point members 20 are provided with the usual points 22. Butts 24 and 26 on these respective members are arranged to be acted upon by dial cams, such as indicated in Figure 2, including the member 28 provided with the cam surface 30 and cams 32, 34 and 36.

The butts of the cylinder needles are arranged to be acted upon by the switch cam 37, the reverse stitch cam 38, the center cam 40, the forward stitch cam 42, the rise cam 44 and the lowering cam 46. As indicated in Figure 1, the needles 4', which are active during rib knitting, pass these cams along the butt path A, their butts passing over the reverse stitch cam 38 and being depressed by cams 40 and 42 to take yarn at the feed of the machine, then being raised by cam 44 and lowered by cam 46. The needles 4'', which are inactive during rib knitting, enter the butt path B and are depressed below the reverse stitch cam 38 by switch cam 37, thereafter moving horizontally to join the butts of the needles 4' to be raised by cam 44 and then lowered by cam 46.

The various structural matters heretofore described will be found to be essentially as disclosed in said Scott patent and details need not be particularly described herein. However, reference may be made to two matters which contribute to the securing of best results and are described in said Lawson application. First, it is desirable, as will appear from Figures 1, 2 and 3 and 5 to 10, inclusive, of the drawings, that the dial needles draw their stitches during rib knitting somewhat later than the cylinder needles which aids in widening the bights between the rib and plain loops and also makes the action of the sawtooth sinkers more positive. Secondly, it is preferable to effect cast-off by means of an outside point 22 rather than by an inside hook as described alternatively in said Scott patent, the result being less stretching of the dial stitches with a resulting tendency to production of wider bights between the rib and plain loops.

In said Lawson application, there is described mechanism, not herein shown, for effecting shogging of the dial with respect to the cylinder while the two rotate together. Such shogging action forms no part of the present invention, and reference may be made to said Lawson application for the effect of this shogging in the production of improved rib fabric in which the dial needle wales, though not positioned midway between the cylinder needle wales, are of substantially the same size, giving rise to improved elasticity and, concurrently, to improved appearance of a more solid and heavier rib fabric devoid of the open ladder-like lines characterizing the rib fabrics heretofore produced on cylinder and dial machines capable of knitting and effecting transfer of loops by means of dial needles such as in the said Scott patent. Briefly stated, in one relative position of the dial and cylinder the needles are in the relative positions illustrated in said

Scott patent suitable for transfer of loops from the dial needles to the cylinder needles. Under these conditions, the dial needles are substantially in the same axial planes as the needles 4'' to which transfer of loops is to be made. 5 Fins 15 are then in the axial planes of plain sinkers 12. These relative positions of the parts, if present during rib knitting, would result in the results heretofore produced and relatively unsatisfactory.

During rib knitting, however, the dial is shogged relatively rearwardly with respect to the cylinder, giving the parts the relative positions illustrated in Figure 3. Under these conditions, it will be noted that the dial needles are no longer in the axial planes of the inactive cylinder needles but, rather, are displaced rearwardly to the end 15 that they are in axial planes close to, and immediately in front of, the active cylinder needles from the standpoint of the direction of rotation, which is to the right of Figure 3. Under these conditions there is also displacement of the fins 15 to bring them substantially in the axial planes of the active cylinder needles 4'. As will be evident from the foregoing, the sawtooth sinkers will then be asymmetrically located with respect to the cylinder and dial needles, the dial needles being spaced to a greater extent than the active cylinder needles from the sawtooth sinkers therebetween.

It will be noted, comparing Figures 1 and 2, that in the formation of stitches the cylinder needles 4' reached their lowermost position under stitch cam 42 at the axial plane 7 which precedes the axial plane 8 at which the hook 30 members 16 reach their innermost stitch drawing positions.

Reference may be made to said Lawson application for details of the operations of the elements giving rise to the improved fabric.

35 Reference may now be made to the sinker controlling devices to which the present invention relates. In Figure 4 the regular forward and reverse knock-over cams are illustrated at 48 and 50, respectively. The former of these is pivoted at 52 and the latter at 54. A rib knock-over cam 56 having its active rise at 58 is pivoted also at 52 independently of cam 48. The reverse knock-over cam 50 is controlled by a link 60 from the main cam drum of the machine in conventional fashion while the forward knock-over cam 48 is similarly controlled by a link 61. The inner position of cam 56 is adjusted by means of the eccentric 70 which abuts a portion of the sinker cap which carries all of the parts of the sinker control system.

50 A control link 62 operated from the main cam drum of the machine is connected to a bell crank 64 which is pivoted at 66. The arm 72 of lever 64 is arranged to engage the end 82 of a lever 84 pivoted at 86, which lever is provided with a slot 88 embracing a pin 90 carried by a cam 92 pivoted at 94. The lever end 82 is provided with 55 a pair of steps 83 and 85 cooperating with arm 72 as will appear hereafter. Various springs, some of which are not shown, act on the levers and cams to urge them against the actions of the mechanical connections which effect their movements.

60 A cam corresponding to 78 is illustrated and described in said Scott patent as having the function when in an outer position of producing withdrawal of sinkers during both the transition from welt to rib top knitting and during the continued knitting of the rib top. In accordance with the present invention this cam 78 remains in an inner position as illustrated in Figure 4.

65 During the knitting of the welt, the lever 64 will occupy an extreme clockwise position clearing both of the steps 83 and 85 of lever 84. As a result cam 92 will 70 occupy an inner position maintaining normal sinker operation, the knock-over cam 48 being in its inner position to impart the proper sinker wave for plain knitting.

Following the end of the welt and at the initiation of rib knitting, the sawtooth sinkers must engage the welt 75 to impart an inward take-up action for the proper for-

mation of rib stitches. To secure this result, the lever 64 is rocked to its extreme counterclockwise position, and the cam 48 is withdrawn, leaving the cam 56 and the sinker spring band to effect the knock-over action. The high step 85 of lever 84 is engaged causing cam 92 to be moved to its extreme outer position. The sawtooth sinkers are thus withdrawn abnormally outwardly by cam 92 so that abnormal tension will be applied by them to the fabric under the action of the sinker spring band and cam 56 during the initial courses of rib knitting to insure passage of the welt beneath the dial.

Extreme outward movements of the sinkers by cam 92 followed by a corresponding extreme inward movement by cam point 58 is undesirable following initiation of rib knitting for reasons which may be explained as follows:

In prior type of operation, before cam 92 was used, the sinkers were withdrawn by a cam corresponding to 78, and in order for the sawteeth to take a new bite on the fabric it was necessary that during passage of the sinkers over the cam they gradually released the tension on the dial stitches until, effectively, the stitches were relatively free and out of control. The release of tension was greatest in the region represented by plane 6 in Figure 4, and since, as seen in Figure 6, the dial member 16 was being moved inwardly by the stitch cam 34 (Figure 2), it was possible for the relatively untensioned loop on the member 16 to slide outwardly toward the hook on the member 18 so that it might be missed by point 22 of member 20, and instead of being held above the hook as in Figure 7 to be cast off, it would be located in the hook with the new loop, thus forming a tuck. Irregularities in the stitches were also possible due to relaxation of tension beginning when the sinkers first contacted the cam corresponding to 78 and the sudden application of new tension as they again came under the influence of the spring band, since during this part of the stitch cycle the hooks, points and cylinder needles were almost continuously changing their relative positions.

According to the present invention, following the initiation of rib knitting as described above, the lever 64 moves clockwise to a sufficient extent to clear the high step 85 of lever 84 while engaging step 83 as illustrated in Figure 4 so that cam 92 is held in an intermediate position. Under these conditions a normal tension for rib knitting is imparted to the fabric by the sawtooth sinkers, the cam 78 merely insuring sufficient clearance between the sawtooth sinkers and fins for the passage of the welt and rib fabric.

According to the invention, cam 92 withdraws the sinkers at a point well past where the stitches are cast off, and since the cylinder needles are down, the dial hooks in, and the fabric triggered by the corners of the dial fins as seen in Figure 10, it is not necessary to withdraw the sinkers nearly as far as was formerly required to insure that the sawtooth will take a new proper bite on the fabric. Cam 78 in its fixed inner position consequently releases the tension only to the extent that the sinkers may have settled inwardly under the influence of the spring band after having passed cam 92, and a substantially continuous tension is therefore maintained during the complete stitch cycle, being released only slightly, if at all, by cam 78 and again when the dial stitches are released as the point members are withdrawn by cam 30. Due to this substantially constant tension applied to the fabric it appears that the spring band becomes more effective in casting off the dial stitches and it is necessary to move the sinkers only slightly by the rib knock-over cam 56. Tucks and irregularities are much less likely to occur.

Following the completion of rib knitting, the lever 64 is moved to its extreme clockwise position, completely clearing lever 84, with consequent removal of cam 92 from effective action. Cam 48 is restored to action for the imparting of proper sinker movements for plain knit-

ting. Cam 50 is also restored to its active position in readiness for knitting the heel and toe.

The shoulders 17 on the fins 14 have the purpose which is best made clear from consideration of Figures 9 and 10. These shoulders engage the stitches of the rib fabric so that as the sawtooth sinkers are withdrawn by cam 92 the fabric is held against outward movement with the sinkers, with the result that after cam 92 is passed the sinkers will take a new engagement with the fabric to effect inward tensioning thereof under the action first of spring 7 and then of cam point 58. It may be here remarked that the sinker movements between the positions determined by cams 92 and 56 are of the order of extent of the spacing of two teeth 8.

It will be evident from the foregoing that the invention is applicable to operation in accordance with the Scott patent as well as in accordance with said Lawson application.

What is claimed is:

1. In a circular knitting machine, a cylinder, a dial, cylinder and dial needles respectively carried thereby, cams for imparting stitch drawing movements to said cylinder and dial needles, sinkers for effecting inward movements of fabric during rib knitting by said cylinder and dial needles, and means for imparting maximum outward movements to said sinkers at a point remote from the location of drawing of stitches.
2. In a circular knitting machine, a cylinder, a dial, cylinder and dial needles respectively carried thereby, cams for imparting stitch drawing movements to said cylinder and dial needles, sawtooth sinkers for effecting inward movements of fabric during rib knitting by said cylinder and dial needles, and means for imparting maximum outward movements to said sinkers at a point remote from the location of drawing of stitches.
3. In a circular knitting machine, a cylinder, a dial, cylinder and dial needles respectively carried thereby, the dial needles being of a type capable of transferring loops to cylinder needles, cams for imparting stitch drawing movements to said cylinder and dial needles, sinkers for effecting inward movements of fabric during rib knitting by said cylinder and dial needles, a knock-over cam for acting upon sinkers at a position adjacent to the location of drawing of stitches, and means for imparting maximum outward movements to said sinkers at a point remote from the location of action by said knock-over cam.
4. In a circular knitting machine, a cylinder, a dial, cylinder and dial needles respectively carried thereby, the dial needles being of a type capable of transferring loops to cylinder needles, cams for imparting stitch drawing movements to said cylinder and dial needles, sawtooth sinkers for effecting inward movements of fabric during rib knitting by said cylinder and dial needles, a knock-over cam for acting upon sinkers at a position adjacent to the location of drawing of stitches, and means for imparting maximum outward movements to said sinkers at a point remote from the location of action by said knock-over cam.
5. In a circular knitting machine, a cylinder, a dial, cylinder and dial needles respectively carried thereby, the dial needles being of a type capable of transferring loops to cylinder needles, cams for imparting stitch drawing movements to said cylinder and dial needles, sinkers for effecting inward movements of fabric during rib knitting by said cylinder and dial needles, and means for imparting outward movements to said sinkers at a point remote from the location of drawing of stitches, said dial being provided with fins having inwardly facing approximately vertical shoulders to hold rib fabric during outward movements of the sinkers.
6. In a circular knitting machine, a cylinder, a dial, cylinder and dial needles respectively carried thereby, the dial needles being of a type capable of transferring loops to cylinder needles, cams for imparting stitch drawing

movements to said cylinder and dial needles, sawtooth sinkers for effecting inward movements of fabric during rib knitting by said cylinder and dial needles, and means for imparting outward movements to said sinkers at a point remote from the location of drawing of stitches, said dial being provided with fins having inwardly facing approximately vertical shoulders to hold rib fabric during outward movements of the sinkers.

7. In a circular knitting machine, a cylinder, a dial, cylinder and dial needles respectively carried thereby, cams for imparting stitch drawing movements to said cylinder and dial needles, sawtooth sinkers for effecting inward movements of fabric during rib knitting by said cylinder and dial needles, and means for imparting movements to said sinkers shortly after the drawing of stitches so that substantially continuous tension is applied to the dial stitches during their cycle of formation.

8. In a circular knitting machine, a cylinder, a dial, cylinder and dial needles respectively carried thereby, cams for imparting stitch drawing movements to said cylinder and dial needles, sinkers for effecting inward movements of fabric during rib knitting by said cylinder and dial needles, and means for imparting outward movements to said sinkers at a point remote from the location of drawing of stitches, the last mentioned means comprising a cam having a plurality of active positions and an inactive position to impart different extents of said outward movements to the sinkers.

9. In a circular knitting machine, a cylinder, a dial, cylinder and dial needles respectively carried thereby, cams for imparting stitch drawing movements to said cylinder and dial needles, sawtooth sinkers for effecting inward movements of fabric during rib knitting by said cylinder and dial needles, and means for imparting outward movements to said sinkers at a point remote from the location of drawing of stitches, the last mentioned means comprising a cam having a plurality of active positions and an inactive position to impart different extents of said outward movements to the sinkers.

10. In a circular knitting machine, a cylinder, a dial, cylinder and dial needles respectively carried thereby, the dial needles being of a type capable of transferring loops to cylinder needles, cams for imparting stitch drawing movements to said cylinder and dial needles, sinkers for effecting inward movements of fabric during rib knitting

5 by said cylinder and dial needles, a knock-over cam for acting upon sinkers at a position adjacent to the location of drawing of stitches, and means for imparting outward movements to said sinkers at a point remote from the location of action by said knock-over cam, the last mentioned means comprising a cam having a plurality of active positions and an inactive position to impart different extents of said outward movements to the sinkers.

11. In a circular knitting machine, a cylinder, a dial, cylinder and dial needles respectively carried thereby, the dial needles being of a type capable of transferring loops to cylinder needles, cams for imparting stitch drawing movements to said cylinder and dial needles, sawtooth sinkers for effecting inward movements of fabric during

15 rib knitting by said cylinder and dial needles, a knock-over cam for acting upon sinkers at a position adjacent to the location of drawing of stitches, and means for imparting outward movements to said sinkers at a point remote from the location of action by said knock-over cam, the last mentioned means comprising a cam having a plurality of active positions and an inactive position to impart different extents of said outward movements to the sinkers.

12. In a circular knitting machine, a cylinder, a dial, cylinder and dial needles respectively carried thereby, cams for imparting stitch drawing movements to said cylinder and dial needles, sinkers between cylinder needles, at least some of which sinkers have saw teeth, and normal pull-out and knock-over cams adjacent to

20 the knitting point to cast off stitches, in combination with means for imparting outward movements to the sinkers, at a location remote from the location of drawing of stitches, to withdraw the sinkers beyond the withdrawal distance effected by said pull-out cam adjacent to the knitting point and then release the sinkers, so that saw tooth sinkers may tension rib fabric without release of the tension by said pull-out cam.
